(57) **CLAIM**

The ornamental design for a braided electrical speaker cable, as shown and described.

DESCRIPTION

FIG. 1 is a perspective view of my new design showing a braided electrical speaker cable with a twisted bare wire connector disposed on opposite ends, thereof;

FIG. 2 is an enlarged view of a portion of a length of the braided electrical speaker cable of FIG. 1; and,

FIG. 3 is an enlarged view of an end portion of the braided electrical speaker cable of FIG. 1.

1 Claim, 2 Drawing SheetsFIG. 1

FIG.2

FIG.3
